UNITED STATES PATENT OFFICE.

SAMUEL GEORGE HOSACK, OF ANN ARBOR, MICHIGAN.

SIDING-GAGE.

SPECIFICATION forming part of Letters Patent No. 399,898, dated March 19, 1889.

Application filed June 21, 1888. Serial No. 277,726. (No model.)

To all whom it may concern:

Be it known that I, SAMUEL GEORGE HOSACK, a citizen of the United States, residing at Ann Arbor, in the county of Washtenaw and State of Michigan, have invented new and useful Improvements in Siding-Gages, of which the following is a specification.

My invention relates to improvements in siding-gages, having for its object to provide a simple, cheap, and easily-operated device which may be quickly and safely secured to the side of the building without the use of a hammer or other tool, thereby economizing the time of the operator.

15 The invention consists in a certain novel construction and combination of devices, fully set forth hereinafter in connection with the accompanying drawing, wherein the figure is a side view, partly in section, of the same applied in the operative position to the siding.

Referring to the drawing, A designates a transverse bar, which is provided with a longitudinal slot, B, extending inward from its outer end, and C represents a spring-rod comprising the short vertical arm D, affixed rigidly at its upper end to the inner end of the bar A, the long vertical arm E extending through the slot B in the transverse bar, and the spring-coil F connecting the lower ends of the said arms and normally pressing the upper end of the longer or movable arm outward. The arms D and E are preferably formed integral with the opposite ends of the spring-coil, as shown clearly in the drawing. A small flat spur, G, is arranged flush with the inner end of the transverse bar, which is inclined or beveled slightly to bear flat against the face of the siding. The siding is inclined outward slightly at its lower edge, and the said spur is adapted to be introduced between the lower edge of the last-nailed board and the face of the board just below, as shown in the drawing.

H represents an adjustable finger, which slides vertically on the arm E, and is adapted to be secured at the desired point by the thumb-screw I, which impinges at its inner end against the said arm, and the inner end of this finger is sharpened to a point to enable it to engage readily in the last-nailed siding-board. A cam-lever, K, is mounted on a trans-

verse pivot, k, in the outer end of the slot B and is adapted to impinge against the outer side of the movable spring-actuated arm E, whereby when the outer or free end of the lever is drawn down the cam k' on the inner end of the lever forces the arm inward and causes the finger H to engage in the surface of the siding.

The operation of the improved gage will now be clearly understood. The distance between the upper side of the adjustable finger and the upper side of the transverse bar A regulates the "weather" or exposed surface of the siding, and having adjusted the finger to show the desired weather the spur G is introduced by a pressure of the hand under the lower edge of the last-nailed siding-board, (the cam-lever being previously arranged in the raised position, as shown in dotted lines in the drawing,) and then the lever is drawn down, thereby causing the pointed end of the finger to penetrate into the surface of the last-nailed siding-board. The next siding-board is now rested on the upper side of the finger and nailed in the ordinary manner.

It will be seen that the gage is secured firmly in place simply by the engagement of the spur and the downward motion of the cam-lever without the use of a hammer or other separate tool, and when the cam-lever is raised the spring at the lower end of the movable arm draws the point of the finger out of the siding-board, thus enabling this tool to be very rapidly operated.

Having described my invention, I claim—

1. In a siding-gage, the combination of the slotted bar A, having an inclined or beveled inner end and provided with the spur flush with the said inner end, the spring-actuated arm passing upward through the slot in the said bar and provided with a pointed finger, and the cam-lever mounted in the slot and adapted to bear against the said arm, substantially as specified.

2. In a siding-gage, the combination, with the transverse bar A, having a slot, B, therein, and provided with a spur, G, of the movable arm E, passing through the slot B and provided at its lower end with a spring-coil, F, connected to the under side of the transverse

bar, the adjustable finger arranged on the said arm, and the cam-lever mounted in the slot B and bearing against the arm, substantially as specified.

- 5 3. The herein-described siding-gage, comprising the transverse slotted bar A, having an inclined or beveled inner end and provided with the flat spur G, flush with the said end, the spring-rod C, provided with the short depending arm D, affixed at its upper end to the inner end of the bar A, the movable arm E, passing upward through the slot in the bar A, and the spring-coil F, connecting the lower ends of the arms D E and serving to press 10 the movable arm outward, the adjustable finger H, mounted on the movable arm and pro-

vided with a thumb-screw to clamp it in the desired position, the inner end of the said finger being pointed to engage the siding, and the cam-lever mounted on a transverse pivot 20 in the outer end of the slot in the bar A and adapted to bear against the movable arm E to force it inward against the strength of the spring-coil and engage the inner end of the finger in the siding, substantially as specified. 25

In testimony that I claim the foregoing as my own I have hereto affixed my signature in presence of two witnesses.

SAMUEL GEORGE HOSACK.
